United States Patent Office.

E. M. MIX, OF WESTFIELD, NEW YORK.

Design No. 2,702, dated July 9, 1867.

DESIGN FOR A RIM-LOCK.

The Schedule referred to in these Letters Patent and making part of the same.

TO ALL WHOM IT MAY CONCERN:

Be it known that I, E. M. MIX, of Westfield, in the county of Chautauqua, and State of New York, have originated a new and improved Design for Rim-Locks, of which the following is a full and exact description, reference being had to the accompanying photographic representations—

Figure 1 being a perspective view, and

Figure 2, an elevation of a lock of my improved design.

Like letters of reference designate corresponding parts in both figures.

My improved design consists in forming the edge of a rim-lock of a moulding, or combination of mouldings, of the following style: First, a cyma-reversa, the concave and convex members of which are divided by a plain fillet, and surmounted by an ovalo with a plain fillet on either side. It also consists in forming a semicircular projection at the top and bottom of the lock-case, surrounding the screw-holes, and in forming the upper and lower ends of the nosing in a semicircular form, with a like moulding to that of the lock-case surrounding its edge.

As represented in the views, *a b* are the members of the cyma-reversa, *c* the intermediate fillet, and *d* the ovalo which crowns them. *E E* are the semicircular projections at the top and bottom, the corners *F F* being left at right angles, and *G G* are the rounded ends of the nosing.

The effect of this design is that of more elaborate finish and richness of execution.

What I claim as my invention, and desire to secure by Letters Patent, is—

The design for rim-locks herein described and shown.

In witness whereof I have hereunto signed my name in the presence of two subscribing witnesses.

E. M. MIX.
